UNITED STATES PATENT OFFICE.

THOMAS R. ROSSITER, OF KNOWLE-BRISTOL, COUNTY OF SOMERSET,
ENGLAND.

SEWING-MACHINE.

SPECIFICATION forming part of Letters Patent No. 414,999, dated November 12, 1889.

Application filed March 26, 1888. Serial No. 268,455. (No model.) Patented in England November 24, 1887, No. 16,196.

To all whom it may concern:

Be it known that I, THOMAS ROBERT ROSSITER, a subject of the Queen of Great Britain and Ireland, residing at Knowle-Bristol, county of Somerset, England, have invented an Improved Sewing-Machine for Making Two Lines of Sewing Simultaneously, (for which I have obtained a patent in Great Britain, No. 16,196, dated the 24th of November, 1887,) of which the following is a specification.

The object of this invention is to provide an improved sewing-machine which will make two lines of sewing simultaneously and very expeditiously.

15 The invention relates to that class of machines in which the under thread is carried by a shuttle mounted so as to have a rotary motion in a horizontal plane, or a plane parallel with the cloth-plate.

20 According to my invention I provide beneath the cloth-plate two such shuttles, each mounted on its carrier and carrying thread, and I mount one of them so that it can be adjusted to make the lines of sewing closer together or farther apart, as desired. The shuttle-carriers are driven from the main shaft by gearing of any suitable description. There are two needles above the cloth-plate, and these needles are also adjustable with respect 25 to each other, so as to be capable of being brought into position one over each of the shuttles.

In the accompanying drawings, Figure 1 is 30 a side elevation of the fore part of a sewing-machine with the cloth-plate and shuttle-races in section, showing the application of my invention thereto. Fig. 2 is a plan of the top side of the cloth-plate with the plates covering the shuttles removed, showing the shuttle in its carrier on one side and the shuttle-carrier without the shuttle on the other side, which is the case also with Fig. 1. Fig. 3 is 35 a plan view of the under side corresponding to Fig. 1; and Fig. 4 is an inverted plan view 40 of the needle-bar with its needles.

A is the fore part of the goose-neck of the machine, through which passes the shaft for driving the needle-bar. The driving devices 45 may be of the usual kind, the needle-bar B being fitted in the head of this goose-neck, as

usual, but carrying two needles, each kept in position by a screw C.

The needles b^2 are received in holes b' , Fig. 4, a series of the said holes being provided, by means of which the needles may be placed at 55 any desired distance apart, in accordance with the width between the two lines of stitches. In the presser-foot D is a slot of sufficient width to allow both the needles b^2 to pass through. The needle-plate or part of the cloth-plate E 60 is provided with holes $e e$, and this can be removed when desired and replaced by another having holes at a distance apart corresponding to the distance apart to which the needles b^2 are adjusted. 65

On the lower shaft for driving the shuttles are two bevel-wheels K K, each of which gears with a bevel-wheel l , fixed on the stem of the shuttle-carrier L.

In the drawings, M is that one of the shuttles which is shown. To alter the shuttles to correspond with the width apart of the needles, the shuttle-race N is adjustable with respect to the other by means of bars n , affixed thereto and sliding in guides in the under 70 casting and secured in position by the screws p . If necessary, both of the shuttles and needles can be made adjustable; but it is only necessary that one should be in practice. The bevel-wheel which drives the adjustable shuttle is 75 capable of being moved longitudinally on the shaft F as the movable part of the machine is being adjusted to alter the distance between the lines of stitches by a bracket k , attached to the said movable part engaging a 80 groove in the boss of the wheel K. The shuttle-driving shaft F is driven from the shaft above or otherwise by any suitable mechanism. (Not shown in the drawings.) It may be 85 of the ordinary description. The machine can thus be readily altered for different widths between the lines of sewing by putting in a cloth-plate with the holes for the needles at the required distance apart, altering the position of the needles, and screwing up the screws 90 C to clamp the needles in place, adjusting the shuttle-race N and fixing it by the screws p . 95

The parts not shown in the drawings or not described may be like or analogous to those used in ordinary sewing-machines. 100

I claim as my invention—

In a sewing-machine, the combination of a needle-bar carrying two needles adjustable with respect to each other, with two shuttle-races, one adjustable toward and from the other, two rotating shuttle-carriers having bevel-wheels and having shuttles in the said races, with a single driving-shaft carrying two bevel-wheels gearing into the wheels on the shuttle-carriers, one of the said wheels being adjustable thereon longitudinally, and a bracket attached to the adjustable shuttle-

race and engaging in a groove in the hub of the said adjustable bevel-wheel, all substantially as and for the purpose set forth.

In testimony whereof I have signed my name to this specification in the presence of two subscribing witnesses.

THOMAS R. ROSSITER.
